UNITED STATES PATENT OFFICE.

ARTHUR R. McARTHUR, OF ELWOOD, INDIANA, ASSIGNOR TO AMERICAN SHEET & TIN PLATE COMPANY, OF PITTSBURG, PENNSYLVANIA, A CORPORATION OF NEW JERSEY.

APPARATUS FOR OPENING PACKS.

976,895.

Specification of Letters Patent. Patented Nov. 29, 1910.

Application filed January 30, 1908. Serial No. 413,405.

To all whom it may concern:

Be it known that I, ARTHUR R. McARTHUR, of Elwood, Madison county, State of Indiana, have invented a new and useful Improvement in Apparatus for Opening Packs, of which the following is a full, clear, and exact description, reference being had to the accompanying drawings, forming part of this specification, in which—

Figure 1 is a plan view of one form of apparatus embodying my invention; Fig. 2 is a side elevation of the same; and Fig. 3 is an end view. Fig. 4 is a longitudinal sectional elevation of the apparatus shown in Figs. 1, 2 and 3. Fig. 5 is a detail plan showing the construction of the beater shafts and arms forming part of this apparatus.

My invention has relation to apparatus for opening sheet metal packs, and is designed to provide apparatus of simple and efficient character, whereby packs may be more rapidly opened.

The precise nature of my invention will be best understood by reference to the accompanying drawings in which I have shown one embodiment thereof, it being premised, however, that various changes may be made therein by those skilled in the art without departing from the spirit and scope of my invention as set forth in the appended claims.

In the drawings, the numeral 2 designates the frame of the machine. Journaled between the side portions of this frame are a plurality of feed-in rollers 3, which are arranged in vertical pairs with their surfaces in contact with each other, the points of contact of adjacent pairs being in different horizontal planes. The upper roller of each pair is preferably journaled in boxes 4, which are vertically movable in guideways 5, of the frame, springs 6 being seated upon said boxes and engaged by adjustable followers 7, whereby the pressure of the rollers may be regulated as may be desired. The rollers are preferably all positively driven in any suitable manner. In the machine shown in the drawings, I have shown the lower rollers as having extended driving shaft connections 8, carrying pinions 9, which respectively mesh with corresponding pinions 10 on the shafts of the upper rollers, these pinions being at opposite sides of the machine for adjacent pairs of rollers.

The rollers 3 are preferably smooth-surfaced rollers. Placed behind the last pair of these rollers 3 is a pair of corrugating rollers 11, having their corrugations running longitudinally thereof, while behind these corrugating rollers are two more pairs of corrugating rollers 12, having their corrugations extending circumferentially thereof. The rollers 11 and 12 are driven by shafts 13, and pinions 14, in a similar manner to the rollers 3. The upper roller of each pair is also preferably vertically adjustable and is held in yielding contact with its fellow by an adjustable spring and follower 15. Behind the last pair of corrugating rollers 12 is a pair of feeding and flattening rollers 16, which are also positively driven by the shaft 17, and pinions 18.

Behind the feeding and flattening rollers 17 are journaled two transversely extending beater shafts 19, each of which carries a series of broad beater blades or arms 20, the two shafts being preferably arranged one above the other. These beater shafts are intergeared at one end by the pinions 21, and are driven by the pulleys 22, 23 and 24 on an extension of the lower beater shaft. The pulleys 22 and 24 are fast to this shaft extension, while the intermediate pulley 23 is a loose pulley. These pulleys are driven by a straight belt 25 and a crossed belt 26 from a belt wheel 27 on a driving shaft 28. Depending in the path of the packs as they pass through the beaters are one or more fingers 29, which are carried by a transverse rocker shaft 30, having an arm 31, which is connected by a link 32, with one arm of a horizontal bell crank lever 33, whose other arm is connected to a belt-shifting bar 34, which engages the belts 25 and 26. 35 designates a pair of feed-out rollers at the delivery end of the machine, said rollers being mounted in vertically adjustable boxes 36, springs 37 being seated upon the upper box with adjustable followers 38, whereby the bite of the rollers may be adjusted as may be desired to suit packs of varying thicknesses.

39 designates suitable guides which extend between the beaters and which guide the packs through the beaters and to the action of the feed-out rollers.

40 is a spring which is connected to an arm of the rock shaft 30, for the purpose of

returning the depending fingers to their normal positions, after they have been operated by the passage of a pack.

The operation is as follows: The packs to be opened are fed into the machine through the series of rollers 3. Owing to the fact that adjacent rollers have their points of contact in different horizontal planes, as before described, the packs in passing through the rollers are subjected to a bending action alternately in opposite directions, after which they pass to the action of the longitudinally corrugated rollers 11, and thence to the action of the circumferentially corrugated rollers 12. By means of these rollers, the packs are corrugated both transversely and longitudinally, this double corrugating combined with the previous bending action serving to loosen the sheets. The packs then pass through the pair of feeding and flattening rollers to the action of the beaters 20. Up to the time the packs are received in the bite of the feed-out rollers, these beaters are acting upon the pack in the direction in which the pack is moving. As the packs pass into the bite of these rollers, however, they actuate the depending fingers 29, and through the described connections, shift the belts 25 respectively from the fast and loose pulleys 23 to the loose pulley 23 and fast pulley 24, so that the beater shafts are now driven by the crossed belt 26 in a direction the reverse to that of their previous rotation. The action of the beaters is therefore reversed, while the packs are passing through the feed-out rollers, the purpose of this reversal being to prevent the kicking and kinking of the sheets by the beaters while they are in the grip of the feed-out rollers. If, at this time, the beaters were revolving in the direction of movement of the pack, the rotation of the beaters at a higher speed than the peripheral speed of the feed-out rollers would tend to kink and kick the sheets, but by reversing the action of the beaters at this time, as described, the loosening effect of the beating action is retained, and thus kicking and kinking is effectually prevented.

By bending the packs in the manner described for corrugating them in both directions, and finally subjecting them to the action of the revolving beaters, the sheets of the packs are loosened and opened in an efficient and rapid manner. I do not limit myself, however, to the particular means herein shown and described for effecting the bending and corrugating of the packs previous to their operation by the beaters, since this may be done in various ways; but I believe myself to be the first to employ beaters, such as described, for acting upon packs after they have been bent or corrugated. It is also obvious that where the bending and corrugating is effected by means of roll-

ers, such as herein described, any suitable number of pairs of bending and corrugating rollers may be employed. The intermediate flattening rollers may be dispensed with and the sheets passed directly from the last corrugating roller to the action of the beaters or additional pairs of flattening and feeding rollers may be employed.

I claim:

1. In apparatus for opening packs, beaters arranged to act upon the packs, and means for rotating the same, substantially as described. 75
2. In apparatus for opening packs, beaters arranged to act upon the packs, means for rotating the beaters, and means for reversing the direction of action of the beaters while they are acting upon the packs, substantially as described. 80
3. In apparatus for opening packs, rotary beaters arranged to act against opposite surfaces of the packs, and means for feeding the packs to the action of the beaters, substantially as described. 85
4. In apparatus for opening packs, means for bending the packs, and rotary beaters arranged to beat the bent packs, substantially as described. 90
5. In apparatus for opening packs, means for bending the packs, and rotary beaters arranged to beat the bent packs, together with means for reversing the direction of rotation of the beaters while they are acting upon the packs, substantially as described. 95
6. In apparatus for opening packs, means for corrugating the packs, and beaters arranged to subsequently beat the opposite sides of the packs, substantially as described. 100
7. In apparatus for opening packs, means for corrugating the packs, and beaters arranged to subsequently beat the opposite sides of the packs, together with means for reversing the action of the beaters while they are acting upon the pack, substantially as described. 105
8. In apparatus for opening packs, rotary beaters arranged to act upon the packs, a pair of feed-out rollers through which the packs pass from the beaters, and means for reversing the direction of rotation of the beaters when the packs enter the bite of the feed-out rollers, substantially as described. 110
9. In apparatus for opening packs, the combination of bending rollers arranged in sets with their passes out of line with each other, corrugating rollers having grooves or corrugations on their outer surface, and rotary beaters arranged to act upon opposite sides of the bent and corrugated packs, substantially as described. 115
10. In apparatus for opening packs, the combination of bending rollers arranged in sets with their passes out of line with each other, corrugating rollers having grooves or corrugations on their outer surface, rotary 120
- 125

beaters arranged to act upon opposite sides of the bent and corrugated packs, a pair of feed-out rollers through which the packs pass after leaving the beaters, and means 5 for reversing the direction of rotation of the beaters as the packs enter the bite of the feed-out rollers, substantially as described.

11. In apparatus for opening packs, the 10 combination of a series of sets of bending rollers having their passes out of line with each other, of corrugating rollers arranged to operate upon the pack subsequently to the bending rollers, said corrugating rollers 15 having grooves or corrugations extending in different directions on different rollers; substantially as described.

12. In apparatus for opening packs, the 20 combination with means for bending the packs, of rotary beaters arranged to act upon opposite sides of the bent packs, gearing arranged to reverse the direction of rotation of the beaters, and shifting devices for the gearing arranged to be engaged and 25 operated by the contact of the packs therewith; substantially as described.

13. In apparatus for opening packs, the 30 combination with means for corrugating the packs, of rotary beaters arranged to act upon opposite sides of the corrugated packs, gearing arranged to reverse the direction of rotation of the beaters, and shifting devices for the gearing arranged to be engaged and 35 operated by the contact of the packs therewith, substantially as described.

14. In apparatus for opening packs, the

combination with means for bending and corrugating the packs, of rotary beaters arranged to act upon opposite sides of the bent and corrugated packs, gearing arranged 40 to reverse the direction of rotation of the beaters, and shifting devices for the gearing arranged to be engaged and operated by the contact of the packs therewith, substantially as described.

45

15. In apparatus for opening packs beaters arranged to deliver blows upon the packs, mechanism for actuating said beaters and means for bodily moving said packs relatively to the beaters; substantially as de- 50 scribed.

16. Apparatus for opening packs, comprising beaters arranged to deliver blows upon the packs and mechanism for rotating said beaters in either of opposite directions: 55 substantially as described.

17. In apparatus for opening packs a plurality of beaters arranged to deliver blows alternately upon opposite sides of the packs and mechanism for actuating said beaters; 60 substantially as described.

18. In apparatus for opening packs rotating beaters arranged to deliver blows upon the packs and mechanism for rotating said beaters; substantially as described. 65

In testimony whereof, I have hereunto set my hand.
